(57) **CLAIM**

The ornamental design for a disposable thyroid cover, as shown and described.

DESCRIPTION

FIG. 1 is a perspective view of a disposable thyroid cover showing my new design;

FIG. 2 is an open top view thereof;

FIG. 3 is an open bottom view thereof;

FIG. 4 is a side view (opposite side view is mirror image) thereof;

FIG. 5 is a front view thereof; and,

FIG. 6 is a back view thereof.

In FIG. 1, the broken lines showing of environmental structure for purposes of illustrating the disposable thyroid cover in a condition of use. The broken lines and the structure they depict form no part of the claimed design.
